UNITED STATES PATENT OFFICE.

HENRY F. JENKS, OF PAWTUCKET, RHODE ISLAND.

DESIGN FOR A GRAVE-MARKER.

SPECIFICATION forming part of Design No. 19,316, dated September 17, 1889.

Application filed July 5, 1889. Serial No. 316,572. Term of patent 14 years.

To all whom it may concern:

Be it known that I, HENRY F. JENKS, of the city of Pawtucket, in the county of Providence and State of Rhode Island, have invented a certain new Design for a Grave-Marker; and I do hereby declare that the following is a full, clear, and exact description thereof, reference being had to the accompanying drawing, and to the letters of reference marked thereon, which form a part of this specification.

The object of my invention is to furnish a tasty and appropriate design for an article to be used to designate the graves of the soldiers who served in the armies of the Union in the late rebellion in this country.

It is illustrated in the accompanying drawing.

The principal feature of this design is a star with five points, each point terminating in a trefoil inclosing a five-pointed star, and the circular medallion center, consisting of an annular space suitable for words and figures. The fifth point of the star is occupied by a figure of a cannon in an upright position, the muzzle being at the top. I place the star in position to have one of its

points at the top, (the one occupied by the cannon,) and the two lowest points are supported by representations of pillars having a base, a column, and a cap upon which the two points of the star rest. From the inner sides of the two lowest points of the star are representations of rings passing through the inner edges of the points and also through the upper corners of an ornamental frame represented as hanging between the two pillars supporting the star. The field inclosed within the ornamental frame is left blank so far as my design goes.

Having thus described my design for a grave-marker, I claim as my invention—

The design for a grave-marker herein shown and described, the same consisting of a representation of the star with a figure of a cannon in place of its uppermost point and supports for its lower points in the shape of two pillars with an ornamental frame supported between them, as set forth.

HENRY F. JENKS.
